UNITED STATES PATENT OFFICE.

MIRAH L. H. DELL, OF LOS ANGELES, CALIFORNIA.

WASHING MACHINE.

Application filed October 30, 1926. Serial No. 145,311.

This invention relates to improvements in laundry machinery, and has particular reference to a device for pre-washing the collars and cuffs of shirts and like garments.

5 The principal object of this invention is to provide means whereby a portion of a garment may be washed previous to the laundrying of the entire garment.

Another object of this invention is to 10 produce a machine wherein a more powerful washing action will take place than is possible with the ordinary tumbler-type of washing machine commonly employed in laundries.

15 A further object is to provide a machine of this character which is simple in construction and therefore cheap to manufacture.

Other objects and advantages will be apparent during the course of the following 20 description.

In the accompanying drawings forming a part of this specification, and in which like numerals are employed to designate like parts throughout the same,

25 Figure I is a side elevation of my machine,

Figure II is a cross-section taken on the line 2—2 of Figure I,

Figure III is a fragmentary vertical cross-section of a portion of my machine,

Figure IV is a top plan view of the clothes holding disc and

Figure V is modified form of the clothes holder.

30 By providing a device of this character only the extremely soiled portions, such as the collars and cuffs are treated and therefore the body portion of the shirt is retained in a presentable condition for a much longer period.

35 In the accompanying drawings wherein for the purpose of illustration is shown a preferred embodiment of my invention, the numeral 5 designates a cylinder supported by legs 6 and 7 upon casters 8 and 9, respectively.

The cylinder 5 has a bottom plate 11 from which depends a receptacle 12 within which the washing fluid is placed. At 13, I have 40 shown a tub having a depending perforated cylinder 14, which cylinder is of less diameter than the receptacle 12. The tub 13 is preferably formed with cup washers 16 and 17, the purpose of which will be later seen.

45 At 18 and 19, I have shown rods which

are secured to the tub 13, which rods are in turn connected by connecting rods 21 and 22, respectively, to crank pins 23 and 24 respectively, carried upon fly wheels 26 and 27, respectively.

These fly wheels are mounted upon a shaft 28 carried in suitable bearings 29 and 31 mounted upon the frame of the device.

A motor 32 is adapted to transmit motion to the shaft 28 through the medium of a plate 33 passing over a suitable pulley positioned on the shaft.

A clothes engaging disc is employed which consists of plates 34 and 36 hinged as at 37 and so arranged that an opening 38 is provided between the same. This disc is adapted to lie upon the bottom of the tub 13 in a manner to be hereinafter described.

Referring to Figure V, the same illustrates a side elevation of a modified form of clothes holder wherein the portions 39 and 41 correspond to the plates 34 and 36. To these plates 39 and 41, are secured semi-circular perforated shell-like members 42 and 43 which are hinged to each other as shown at 44 and 46.

The manner of operating the device is as follows:

The clothes are gathered in such a manner that the collars and cuffs are together, after which the disc is moved to its open position and the clothes are laid between the two sections of the disc so that the collars and cuffs project through to one side thereof, after which the plates 34 and 36 are swung to closed position as shown in Figure IV. The clothes and fluid are now placed in the tub so that the cuffs and collars project into the cylinder 14, while the main portion of the clothes remain in the tub and out of the liquid contained in the receptacle. The motor 32 is now started with the result that reciprocating motion is transmitted to the rods 18 and 19, which results in the tub 13 being moved upwardly and downwardly.

Upon the upward movement the liquid in the cylinder 12 is drawn out due to the vacuum formed in the cylinder. Upon the downward movement of the tub, this liquid is again forced into the cylinder by the pressure set up by the air confined beneath the washer 17.

It is of course understood that this vacuum and pressure are quickly destroyed by the air entering and escaping through the slot 110

38 and the clothes contained therein. Nevertheless, the same is sufficient to cause the washing fluid to surge back and forth through that portion of the clothes extending beneath the plate.

5 In the modified form shown in Figure V, the plate and shell are fastened together and thereafter the clothes and the shell are inserted in the machine and removed as a 10 unit after which the clothes are pre-washed and transferred to the customary washing machine where the remainder of the garment is given its usual washing.

15 It is to be understood that the forms of my invention herewith shown and described are to be taken as preferred example of the same and that various changes relative to the shape, material, size and arrangement of parts may be resorted to without departing 20 from the spirit of the invention or the scope of the subjoined claims.

Having thus described my invention, I claim:

25 1. In a washing machine of the character described, a cylinder, a tub adapted to be reciprocated in said cylinder, a depending portion secured to said tub and adapted to reciprocate therewith and serving to accommodate a portion of the clothes positioned 30 within said tub, a fluid holding receptacle

surrounding said depending portion and formed integral with said cylinder.

2. In a washing machine of the character described, a cylinder, a receptacle depending from the bottom of said cylinder and connected with the interior of the same, a tub positioned within said cylinder and adapted to be reciprocated therein, a shell depending from said tub and receivable in the depending receptacle, a plate positioned within 40 said tub, said plate having an opening therein adapted to accommodate a portion of the garments placed within said tub and means for reciprocating said tub.

3. In a washing machine of the character described, a cylinder, a tub adapted to be reciprocated in said cylinder, means for sealing one edge of said tub to said cylinder, a fluid receptacle positioned beneath said cylinder and formed integral therewith, a 50 plate positioned within said tub, said plate having an opening therein adapted to accommodate a portion of the garments placed within said tub, a shell depending from said tub and extending into said receptacle for receiving the remaining portions of the garments, and means for reciprocating said tub for the purpose specified.

In testimony whereof I affix my signature.

MIRAH L. H. DELL.
